UNITED STATES PATENT OFFICE.

FRED C. SAULS, OF NEW YORK, N. Y.

SHADE-GUARD.

1,117,096.

Specification of Letters Patent. Patented Nov. 10, 1914.

Application filed November 26, 1913. Serial No. 803,285.

To all whom it may concern:

Be it known that I, FRED C. SAULS, a citizen of the United States, residing at New York city, in the county of New York and State of New York, have invented new and useful Improvements in Shade-Guards, of which the following is a specification.

The general object of this invention is to effect the even and constant winding of a window shade upon its roller. And to this end the invention consists of a cap provided with a flange and further provided with means for the securing thereof upon the shade roller.

Other objects will appear and be better understood from that embodiment of my invention of which the following is a specification, reference being had to the accompanying drawings, forming part hereof in which:

Figure 1 is an elevational view of a window sash and shade, having a portion of the shade broken away in order to show the guard mounted on the roller. Fig. 2 is an enlarged detail view of a portion of a shade-roller with the guard mounted thereon. Fig. 3 is a vertical cross-sectional view taken on the line 3—3 in Fig. 2 and also showing a portion of the window shade. Fig. 4 is a perspective view of the guard.

As is usual, upon a window shade being raised, it automatically winds around its roller, and while so doing, it very frequently winds so the coils on the roller overlap each preceding one, with the result that the wound-up portion is being gradually extended and binds against the sash of the window. Again when the shade is accidentally unrolled to its limit it usually becomes torn from its roller for the reason that no means is employed for securing the end of the shade to the roller other than the usual method of tacking. To obviate these occurrences, a guard 5 is provided which is adapted to be mounted on the roller 6 of the shade 7. This guard consists of a sleeve 8 and a flange 9, which is secured to the end of the sleeve or body-portion by solder or

the like. This sleeve or body-portion is formed of a suitable material such as tin, 50 and is provided with a space 10, which admits of the expansion of the sleeve when the same is placed over the roller. This space is also provided for the purpose of allowing the end of the shade to pass 55 through when the sleeve is secured to position as shown in Fig. 3. The sleeve is also provided with a plurality of teeth 11, which are struck up from the tin and are directed inwardly so that upon the sleeve being 60 turned, when in position on the roller, the said teeth will bite thereinto and thus secure the guard in place.

The flange 9 is annular in shape and is of such diameter as that of the shade when 65 wound on the roller. An opening 12 is centrally disposed in the flange, and is adapted to admit the projection therethrough of the roller, as shown in Figs. 1 and 2. The guard in no way conflicts with the keepers 70 13—13 on the window-sash and into which is journaled the ends of the shade-roller.

As shown in Fig. 1, as the shade is raised, and automatically winds around the roller, the flange 9 prevents the edges of the shade 75 fabric from overlapping the preceding coils and obviously the shade will be wound evenly upon the roller.

What is claimed as new is:

A shade-guard consisting of a tubular 80 body portion adapted to be positioned on one end of a shade-roller, a guard flange provided with a centrally disposed opening for receiving the end of the shade roller, the said flange being of greater diameter than 85 the body portion, and spaced teeth struck up on the said body portion for interlocking the shade-guard with the shade-roller when turned in one direction.

In testimony whereof I affix my signature in presence of two witnesses.

FRED C. SAULS.
